UNITED STATES PATENT OFFICE.

HENRY BEHRENS, OF PESHTIGO, WISCONSIN.

ENGINE STAND AND BURNING-IN MACHINE.

1,420,074.

Specification of Letters Patent. Patented June 20, 1922.

Application filed October 28, 1920. Serial No. 420,102.

To all whom it may concern:

Be it known that I, HENRY BEHRENS, a citizen of the United States, and resident of Peshtigo, in the county of Marinette and State of Wisconsin, have invented certain new and useful Improvements in Engine Stands and Burning-In Machines; and I do hereby declare that the following is a full, clear, and exact description thereof.

10 My invention relates to a stand and burning-in machine for engines of the internal combustion class, and its object broadly is to provide a device by which the engine will be more conveniently manipulated.

15 One of its special objects is to provide a stand which is universally adjustable so as to receive any size or type of engine, and to hold it in any position which may be convenient for the mechanic working thereon.

20 Another object is to provide a device which may be adjusted to any crank shaft to drive the same for the purpose stated.

In describing my invention reference will be had to the accompanying drawings, in

25 which:

Figure 1 is an end elevation of the device.

Figure 2 is a longitudinal vertical section on the line 2—2 of Figure 1.

30 Figure 3 is an end elevational view on the opposite end from Figure 1.

Figure 4 is a sectional detail view on the line 4—4 of Figure 3.

Figure 5 is a sectional detail view on the line 5—5 of Figure 2.

35 Figure 6 is a sectional detail on the line 6—6 of Figure 5, and

Figure 7 is a front elevation of one end of the device.

Like reference characters refer to like

40 parts throughout the various views.

The device of which my invention forms a part comprises a base 10 supported on rollers 11. On this base is mounted a frame comprising end members 12 and 13, which

45 are rigidly connected by the longitudinal members 14 and 15. The end members 12 and 13 terminate at the upper end in a cradle formed by the semi-circular members

16 and 17, which rotatively support the circular members 18 and 19.

To these semi-circular members are rigidly attached the dove tail members 20, on which are slidably supported the brackets 21. To these brackets are riveted the channel bars 22, each

55 channel bar being provided with a bracket 23 which is adjustably held by means of

a set screw 24. On the brackets 23 are mounted the clamp jaws 25, which are adjusted by the screws 26 and 27, and passing through the bracket 23 is a rod 28 which is held in any desired position of adjustment by the set screw 29.

The upper end of the rod 28 carries a block 30, which supports a rod 31 which is held in any desired position by the set screw 32. On the end of the rod 31 is carried a block 33, which supports the clamp jaws 34, the jaws being adjusted by the screws 35 and 36.

The circular members 18 and 19 are held in the cradle by the complementary semi-circular members 37 and 38, which are adjustably attached to the cradle members by means of bolts 39. The head of one of the bolts 39 carries a pin 40, on which is mounted the eccentric 41 which has a projecting arm 42 to which is pivotally connected a rod 43. This rod 43 is yieldingly held in its lowermost position by the compression spring 44. Thus it will be seen that the circular members 18 and 19 which carry the frame which supports the engine are yieldingly held in the cradle in any position to which they may be adjusted. If it be desired to change the position of the engine, the pedal 45 may be actuated to raise the rod 43 against the tension of the spring 44 thus releasing the circular members 18 and 19 so that they may be rotated.

Integrally connected to the end members 12 are the vertical guide ways 46 on which slides the frame 47, the latter being adjusted by means of a screw 48 which engages the screw threaded bracket 49 on the frame 12. The frame member 47 is provided with the horizontal guide ways 50 on which slides the frame 51, the latter being adjusted by means of a set screw 52 which is mounted in the bracket 53 rigidly attached to the frame 47. Thus it will be seen, that the frame 51 may be adjusted horizontally and vertically to any position desired.

The frame 51 carries a horizontal shelf 54 on which is mounted the motor M, which drives the gear 55. The gear 55 drives the gear 56 which is mounted on the shaft 57, which in turn is connected through the transmission mechanism 58 to the shaft 59. Said shaft 59 is provided at its opposite end with a member 60 which engages the crank shaft of the engine E, as shown in broken lines in Figure 2. It will be understood that as many clamps may be provided as are

necessary to hold the engine rigidly in position. The two series of clamps 25 and 34 are provided for engaging different parts of the engine or for holding the engine in different 5 positions as illustrated in Figure 5. The stand is thereby made universally applicable to any size or type of engine.

I have described the principle of my invention, together with the apparatus which I 10 now consider represents the best embodiment thereof, but I desire it understood that my invention is not limited to that particular form of the device herewith shown and described, the same being merely illustrative, but that the invention includes all 15 equivalent instrumentalities coming within the scope of the appended claims.

I claim:

1. In a device of the class described, a 20 frame, means for clamping an engine thereon and means for turning the crank shaft of said engine, said last named means being adjustable horizontally and vertically so that it may be adjusted to the crank shaft 25 of any size or type of engine.

2. In a device of the class described, a 30 frame, a supplemental frame rotatably mounted thereon, bars mounted on said supplemental frame and adjustable toward and away from each other, clamps carried by said bars, said clamps being universally adjustable, and means for turning the crank shaft of an engine held by said clamps, said last named means being adjustable horizontally and vertically so that it may be adjusted to the crank shaft of any size or type of engine.

3. In a device of the class described, a 40 frame, a supplemental frame rotatably mounted thereon, bars mounted on said sup-

plemental frame and adjustable toward and away from each other, clamps carried by said bars, said clamps being capable of a bodily rectilinear adjustment, and means for turning the crank shaft of an engine held by said clamps, said last named means being adjustable horizontally and vertically so that it may be adjusted to the crank shaft 45 of any size or type of engine.

4. In a device of the class described, a 50 frame, a supplemental frame rotatably mounted thereon, bars mounted on said supplemental frame and adjustable toward and away from each other, clamps carried by said bars, said clamps being capable of a bodily rectilinear adjustment and also capable of angular adjustment, and means for turning the crank shaft of an engine held by said clamps, said last named means being adjustable horizontally and vertically so 55 that it may be adjusted to the crank shaft of any size or type of engine.

5. In a device of the class described, a 60 frame, a supplemental frame rotatably mounted thereon, bars mounted on said supplemental frame and adjustable toward and away from each other, clamps carried by said bars, said clamps being capable of a bodily rectilinear adjustment and also capable of angular adjustment in two planes, and 65 means for turning the crank shaft of an engine held by said clamps, said last named means being adjustable horizontally and vertically so that it may be adjusted to the crank shaft of any size or type of engine.

In testimony that I claim the foregoing I have hereunto set my hand at Peshtigo, in the county of Marinette and State of Wisconsin.

HENRY BEHRENS.
